UNITED STATES PATENT OFFICE.

JOSEPH R. BLAINE, OF CHICAGO, ILLINOIS, ASSIGNOR TO MIEHLE PRINTING PRESS AND MANUFACTURING COMPANY, OF CHICAGO, ILLINOIS, A CORPORATION OF ILLINOIS.

INKING MECHANISM.

Application filed August 17, 1921. Serial No. 492,883.

To all whom it may concern:

Be it known that I, JOSEPH R. BLAINE, a citizen of the United States, residing at Chicago, in the county of Cook and State of Illinois, have invented certain new and useful Improvements in Inking Mechanism, of which the following is a specification.

This invention relates to printing presses, and more particularly to inking mechanism therefor.

One object of the invention is to simplify and improve mechanism for transferring ink from the ink fountain to the inking rolls whereby the ink may be conveyed and distributed in a manner to meet the requirements for good printing.

Another object is to provide a simple, efficient and durable arrangement whereby the ink transfer rolls may be automatically withdrawn, applied and positioned with respect to inking rolls.

These and other objects are accomplished by means of the arrangement disclosed on the accompanying sheet of drawings, in which—

Figure 1 is a fragmentary side elevation of a printing press embodying my invention; and,

Figure 2 is a fragmentary end elevation of some of the parts shown in Figure 1.

The various novel features of my invention will be apparent from the following description and drawings and will be particularly pointed out in the appended claims.

Referring to the figures of the drawings, it will be noted that I have disclosed my invention in connection with a printing press having a frame 10, in which a plate cylinder 11 is revolvably mounted. Cooperating with the plate cylinder 11 are inking rolls 12, vibrating rolls 13 and rider rolls 14. Ink is ultimately conveyed to the inking rolls from a fountain 15 by a ductor roll 16 to an ink drum 17, which in turn conveys ink to two transfer rolls 18 and 19.

The invention here involved relates primarily to the arrangement and mounting of the ink drum 17 and transfer rolls 18 and 19. These three rolls as a unit are slidably mounted with a frame 20 so that said ink drum and transfer rolls may be removed from the inking rolls (considering rolls 12, 13 and 14 generally as such) in a manner such that the transfer rolls automatically clear the inking rolls and when moved back

into cooperative association with the inking rolls, the transfer rolls automatically position themselves with respect to the inking rolls. In this connection attention is called to the fact that the arm 21, in which the transfer roll 18 is mounted, is loosely mounted upon a journal 22 of the ink drum, as is also an arm 23 carrying the transfer roll 19. Pivotedly connected to the arm 21 is a rod 24, one end of which loosely passes through an opening in a bracket 25 secured to the frame 20. Surrounding the rod 24 is a spring 26, which normally is compressed between a collar 27 on the rod 24 and the bracket 25, so that the transfer roll 18 is yieldably pressed and held in engagement with one of the rider rolls 14. One end of a rod 28 is pivotally connected to the arm 21 and passes through an apertured lug 29 on arm 23, there being a spring 30 surrounding the rod 28 and normally compressed between a nut 31 on the rod 28 and the ear 29 whereby the transfer roll 19 is yieldably pressed and held in engagement with another rider roll 14. Also normally a shoulder 32 formed on the rod 28 is spaced from the apertured lug 29. If it is desired to remove the inking drum and transfer rolls from the straddled position over the inking rolls, the same may be done by means of the arrangement shown without manually handling each one of the rolls separately, the transfer rolls 18 and 19 automatically riding over their respective associated rider rolls and clearing same in an automatic manner greatly facilitating the operation.

Let it be assumed that it is desired to move the inking drum and transfer rolls 18 and 19 to the left and away from the inking rolls. This is done by sliding the frame 20 on the frame 10. During such operation the transfer roll 18 will ride downwardly on its associated rider roll 14, during which movement the compressed spring 26 will force the rod 24 downwardly until the stop nut 33 engages bracket 25, during which downward movement of the rod 24 the arm 21 is rotated in a counterclockwise direction, as viewed in Figure 1. At the same time the space between the ear 29 on arm 23 and the collar 32 on rod 28 will have been taken up, thereby forming a rigid connection between the arm 21 and the arm 23, whereby the latter likewise will be rotated in a counterclockwise direction for clearing the asso-

ciated rider rolls 14, the ink drum and transfer rolls 18 and 19 then assuming the position as shown in dotted lines at the left-hand side of Figure 1.

5. To return the ink drum 17 and transfer rolls 18 and 19 to their normal operative positions and have them automatically assume their proper respective positions, the unit is moved to the right, the transfer roll 19 maintaining its elevated position until the other transfer roll 18 passes into engagement with its associated rider roll 14. As the transfer roll 18 rides up on its associated rider roll 14, its arm 21 is rotated in a clockwise direction, compressing the spring 26 and likewise compressing the spring 30 for yieldably forcing the other transfer roll 19 into engagement with its associated rider roll 14.

The operations are entirely automatic in that it is unnecessary to handle each one of the rolls separately for placing and withdrawing the transfer rolls with respect to their straddled position on rider rolls of the set of inking rolls. Attention also is called to the fact that when the form rollers are tripped or raised out of engagement with the form cylinder 11, the transfer rollers 18 and 19, by reason of the springs 26 and 30, automatically maintain their contact with the associated form rider rollers 14 without causing any binding action or undue pressure of the parts. Also by means of this inking arrangement the ink is supplied from the ink drum to the inking rolls in two separate paths, one through the transfer roll 18 and the other through transfer 19, whereby an improved inking is provided.

It is my intention to cover all modifications of the invention falling within the spirit and scope of the following claims.

I claim:

1. In a printing press, the combination of a plate cylinder, inking rolls associated therewith, and yieldably interconnected transfer rolls for transferring ink to said inking rolls and mounted in a manner whereby they automatically position themselves when applied to said inking rolls.

50. 2. In a printing press, the combination of a plate cylinder, inking rolls associated therewith, and yieldably connected transfer rolls for transferring ink to said inking rolls and swingably mounted in a manner whereby they may automatically clear themselves from said inking rolls when withdrawn therefrom.

60. 3. In a printing press, the combination of a cylinder, inking rolls associated therewith, and transfer rolls yieldably connected to each other and straddling said inking rolls for transferring ink to said inking rolls and mounted in a manner whereby they automatically position themselves when applied to said inking rolls and automatically

clear themselves from said inking rolls when withdrawn therefrom.

4. In printing press inking mechanism, the combination of a plurality of laterally movable transfer rolls yieldably interconnected with respect to each other to automatically position themselves with respect to associated rolls when applied thereto.

5. In printing press inking mechanism, the combination of a plurality of laterally movable transfer rolls yieldably interconnected with respect to each other to automatically clear associated rolls when withdrawn therefrom.

6. In printing press inking mechanism, the combination of a support, arms pivotally mounted on said support, transfer rolls mounted in said arms, and means connecting said arms whereby one of said arms will have a lifting effect upon the other for clearing one of said transfer rolls with respect to an associated roll.

7. In printing press inking mechanism, the combination of a support, a plurality of arms pivotally mounted on said support, laterally movable transfer rolls carried by said arms, and means acting upon said arms for yieldably pressing said rolls into engagement with associated rolls and causing said transfer rolls to position themselves with respect to associated rolls when given a lateral movement to and from normal operative position.

8. In printing press inking mechanism, the combination of a support, arms pivotally connected to said support, transfer rolls mounted in said arms, means for yieldably pressing one of said arms for forcing its roll into engagement with the associated roll, and a yieldable connection between said two arms for forcing the second transfer roll into engagement with an associated roll.

9. In printing press inking mechanism, the combination of an ink drum having a trunnion, a plurality of arms supported on said trunnion, transfer rolls carried in said arms and engaging said ink drum, means for yieldably pressing one of said arms for forcing its roll into engagement with an associated roll, and a yieldable connection between said arms for pressing the other transfer roll into engagement with an associated roll.

10. In printing press, the combination of inking rolls, a plurality of transfer rolls for transferring ink to said inking rolls and straddling the latter, and means whereby said transfer rolls may be withdrawn laterally from said inking rolls whereby the former will clear the latter.

11. In a printing press, the combination of inking rolls, a plurality of transfer rolls for transferring ink to said inking rolls and straddling the latter, and means whereby said transfer rolls may be applied in a

straddling position with respect to said inking rolls and automatically position themselves with respect thereto.

12. In a printing press, the combination of an ink drum, inking rolls, and means for transferring ink from said ink drum to said inking rolls through two separate paths and including yieldably interconnected transfer rolls.

10 13. In a printing press, the combination of inking rolls, an ink drum, and a plurality of laterally movable transfer rolls yieldably connected to each other and engaging said ink drum and transferring ink to said

inking rolls through a plurality of different 15 paths.

14. In a printing press, the combination of inking rolls, transfer rolls engaging certain of said inking rolls, and a yieldable connection between said transfer rolls 20 whereby engagement between said transfer rolls and inking rolls may be maintained when the latter are tripped without causing any binding action of any parts.

Signed at Chicago, Illinois, this 12th day 25 of August, 1921.

JOSEPH R. BLAINE.
